UNITED STATES PATENT OFFICE

154,836

DESIGN FOR A PIANO OR SIMILAR ARTICLE

Alexander P. Brown, Beechhurst, N. Y.

Application April 26, 1947, Serial No. 138,648

Term of patent 14 years

(Cl. D56—9)

To all whom it may concern:

Be it known that I, Alexander P. Brown, a citizen of the United States, residing at Beechhurst, in the county of Queens and State of New York, have invented a new, original, and ornamental Design for Piano or Similar Article, of which the following is a specification, reference being had to the accompanying drawing, forming part thereof.

Fig. 1 is a perspective view of a piano or similar article showing my new design, the sheet music drawer being shown as it appears in open or extended position.

Fig. 2 is a rear elevational view.

Fig. 3 is top plan view in closed position, the right side of top and the case being indented.

I claim:

The ornamental design for a piano or similar article, substantially as shown and described.

ALEXANDER P. BROWN.
